UNITED STATES PATENT OFFICE.

WILLIAM H. WATROUS, OF HARTFORD, CONNECTICUT.

DESIGN FOR A SPOON.

SPECIFICATION forming part of Design No. 21,052, dated September 22, 1891.

Application filed August 17, 1891. Serial No. 402,904. Term of patent 7 years.

To all whom it may concern:

Be it known that I, WILLIAM H. WATROUS, a citizen of the United States, residing at Hartford, in the county of Hartford and State 5 of Connecticut, have invented and produced a new and original Design for Spoons, of which the following is a specification, reference being had to the accompanying drawings, forming a part thereof.

10 Figure 1 is a top or plan view of the upper side of a spoon embodying my design. Fig. 2 is a plan view of the back of the spoon, also showing features of my design.

In the accompanying drawings, the letter *a* 15 denotes the handle of the spoon, *b* the shank or narrow portion of the handle, and *c* the bowl. On the broad upper end of the handle is shown in relief a representation of an oak-tree, the irregular outline of the tree forming 20 the edge of the handle of the spoon near the upper end, with the base of the tree also projecting slightly at points farther along the handle. Along the shank or narrow part of the handle there is left a space that may be 25 filled with any desired printed matter, as the words "Hartford, Conn." The bowl *c* is of irregular outline, resembling the outline of an acorn, and within the bowl is depicted on a shield the motto of the city of Hartford, 30 comprising the representation of a hart crossing a shallow stream and the motto of the city. On the reverse side of the spoon, at the upper end of the handle, there is shown in re-

lief foliage that extends downward along the handle toward the shank, the ends of the 35 leaves projecting and corresponding with the irregular outline created by following the outline of the tree and the roots shown on the obverse of the spoon-handle. At the upper part *d* of the bowl there is shown in relief the representation of the base of an acorn. 40

The whole forms a design for a spoon having as characteristic features the representation of the Charter Oak and a bowl formed in representation of an acorn. 45

I claim as my invention—

1. The design for a spoon, comprising a handle forming at its outer end on the obverse side a representation in relief of an oak-tree, and the bowl bearing the delineation of 50 the seal of the city of Hartford, the edges of the bowl conforming to the outline of an acorn, as described and set forth.

2. The design for a spoon, comprising a handle having on the reverse side at the upper end the representation in relief of foliage, 55 the edges of the handle conforming to the outline of the leaves along one side of the handle, and the reverse of the bowl bearing the representation of an acorn, as described 60 and set forth.

WILLIAM H. WATROUS.
